MACHINE TO MAKE TYPE SHUTTLES FOR
TYPEWRITING MACHINES

Henry L. Pitman, Westfield, N. J., assignor, by
mesne assignments, to Ralph C. Coxhead Cor-
poration, New York, N. Y., a corporation of
Delaware

Application March 19, 1931, Serial No. 523,921

44 Claims. (Cl. 101—401.5)

This invention relates to an automatic machine to make type carriers or shuttles, such as illustrated in my application No. 523,919 filed March 19, 1931, for typewriting machines of the kind known as the Varityper.

The invention also includes features similar to those disclosed in my application No. 523,920 filed March 19, 1931, in which one or more shuttle blanks are placed in a die secured to a chuck where the blanks are then operated upon by suitable rolling means to flow the metal of the shuttle blanks into type intaglions on the die, to thus form raised types on the shuttles. Said roller means is hand operated and is also hand adjusted to increase its pressure on the shuttles as the rolling operation proceeds.

An object of the present invention is to provide an automatic machine whereby the production of the shuttles is expedited. To this end there is provided a motor which is connected, through suitable mechanism, to oscillate the roller means.

Provision is made to automatically increase the pressure of the roller mechanism as the rolling operation proceeds.

Means are also provided to automatically render the pressure increasing means ineffective when the shuttles have been rolled to a predetermined thickness.

Other features and advantages will hereinafter appear.

In the drawings which form part of the specification,

Fig. 1 is a vertical section of the machine;

Fig. 2 is a top plan view of the machine showing the chuck open and the die sections separated;

Fig. 3 is a sectional top plan view taken on the line 3—3 of Fig. 1 showing the oscillating means in a different position;

Fig. 4 is a detail view showing the pawl and ratchet mechanism of the pressure increasing means;

Fig. 5 is a perspective view of the chuck;

Fig. 6 is a top plan view of the chuck showing the die gripped thereby;

Fig. 7 is a detail, sectional view taken on the line 7—7 of Fig. 6, some of the parts being omitted;

Fig. 8 is a top plan view of the shuttle showing the types formed thereon; and

Fig. 9 is a vertical section of the shuttle at the line 9—9 of Fig. 8.

Similar reference characters represent similar parts throughout the several views.

The machine includes a frame 15, having a base 16 from which extend standards 17 to support a top plate or table 18. A chuck 19 is mounted upon the top plate 18 and secured thereto by screws 20. Said chuck includes four jaws 21 (Figs. 1, 5 and 6) each secured to a rack 22, the racks being guided in slots 23 of said chuck. The racks 22 engage with a spiral 24 formed on the face of a bevel gear 25 so that the jaws may be moved inwardly, by rotating the gear 25, to grip a die 26, or they may be moved outwardly thereby to release the die.

The jaw operating gear 25 may be rotated by one or more gears 27, each being provided with a polygonal shaped aperture 28 to receive a key 29 by which the gear 27 may be rotated.

The die 26 may be like that described in my application No. 523,920 above referred to and comprises four sections 30, 31, 32 and 33 which sections when assembled as in Fig. 6 form a circular aperture 34 into which the shuttles 35, in blank form, are placed to be operated upon by rollers 36 of the roller means 37, hereinafter described, to flow the metal of the shuttles into types 38, in intaglio on the concaved surfaces of the die sections, to thus form the types 39 on the shuttles. Each die section has tongues 40 and 41 extending crosswise of each other and into corresponding grooves 42 and 43 in the end of the adjacent die sections to thus interlock the die sections to prevent relative shifting during the shuttle rolling operation.

The roller means 37 includes two roller carriers 44 (Figs. 1 and 6) having slots or grooves 45 in which the rollers 36 are supported by shafts 46. The roller carriers 44 are slideable in a transverse, inverted T-slot 47 (see Fig. 7 also) of a holder or head 48 on the upper end of a vertical spindle or hollow shaft 49 which is supported for oscillation in a bearing 50 in the top plate 18, and a bearing 51 of a bracket 52 secured to the base plate 16; the oscillating means for the shaft 49 being hereinafter described.

When the die, with the shuttle blank therein, is to be placed in the chuck, the roller carriers 44 are brought to their contracted positions. They are subsequently spread apart by a wedge or cam 55 pivotally supported on a reduced portion 56 of an actuator shaft 57 extending through the sleeve 49; the shaft 57 being moved up and down in said sleeve, in a manner hereinafter described, to adjust the wedge 55. The wedge 55 in plan, is rectangular (Fig. 6) and has sloping sides 58 engaging correspondingly sloping faces 59 in the bottom of slots 60 formed in the ends of the roller

carriers 44, so that as said wedge is moved upwardly in Fig. 1 it spreads the roller supports 44 to press the rollers 36 against the shuttles.

To actuate the shaft 57 and thus expand the 5 roller means after the shuttles are in position in the die, there is provided a hand wheel 61 secured to a shaft 62 to rotate the latter; the shaft 62 being supported in a web 63 of the machine frame and a bearing 64 of the bracket 52. The 10 shaft 57 has secured thereto a bevel gear 65 which meshes with and rotates a gear 66, the latter comprising a nut 66^a operating on a thread 67 of the shaft 57 to raise the shaft 57 and thus carry the wedge 55 therewith to spread the roller carriers 44 until the rollers 36 engage the back of the shuttle. It will be understood that if the gear 66 is rotated in the opposite direction the shaft 57 and the wedge 55 are lowered so that the roller means may be contracted. The shaft 20 57 is held against rotation, when acted upon by the nut 66^a, by the reduced end 68 of a screw 68^a, said screw end extending into a slot 68^b in the lower end 69 of the shaft 57 which engages in a hole 69^a of a boss 69^b formed on the base 16 of 25 the machine frame. It will be understood that the gear 66 is confined between the bearing 51 and the boss 69^b to insure the up and down movement of the shaft 57.

To prevent dislodgement of the roller carriers 30 44 from the top of slot 47 by the action of the wedge, two guide plates 70 are secured to the head or support 48 by screws 70^a, and each carrier is provided at its lower end with flanges 70^b engaging in lateral extensions of the slot 47. The plates 35 70 and the flanges 70^b also assist to guide the roller carriers accurately while moving outwardly therein. Upward movement of the sleeve 49, which would otherwise be produced by the wedge 55, through the head 48, is prevented by a 40 collar 71 secured to said sleeve and engaging the bottom of the chuck 50 which, it will be remembered, is secured to the table 18 by the screws 20.

After the roller means has been expanded sufficiently to just touch the shuttle blanks, the 45 rolling operation may be started. To this end there may be provided a switch 72 connected in an electric circuit comprising conductors 72^a and 72^b extending from a source of power to a motor 73. The motor shaft 74 is supported 50 in a bracket 75 and has secured thereto a worm 76 which drives a worm wheel 77 secured to a shaft 78 supported in a bracket 79. A disk 80 secured to the shaft has connected thereto one end of a link 81 by means of a headed stud 80^a, 55 the other end of the link 81 being connected to an arm 82 secured to the sleeve 49 so that as the disk continues to rotate the sleeve 49 and the roller means carried thereby are oscillated to carry the rollers back and forth over 60 the shuttles. As the rolling operation continues the shuttles become thinner and from time to time it is necessary to spread the roller means slightly to press the roller against the shuttles. This may be effected manually by means of the 65 hand wheel 61 or it may be effected automatically in a manner now to be described.

The automatic means for increasing the pressure of the rollers 36 against the shuttles from time to time may include a ratchet wheel 83 (Figs. 70 1 and 4) secured to the shaft 62; said ratchet being operable by a pawl 84 pivoted by a stud 85 on an arm 86 loosely supported on the shaft 62 so that it may be oscillated back and forth on said shaft 62, by means hereinafter described, 75 to feed the ratchet 83 and the connected shaft

62 and thus feed the shaft 57 upwardly through the medium of the gears 65 and 66 to spread the roller carriers by the wedge 55.

To oscillate the pawl carrying arm 86 there is connected to it, through the stud 85, a link 87 which link is connected to a crank 88 by a stud 89. The crank 88 is secured to a shaft 90 rotatably supported in the web 63 and in a bearing 91 of the bracket 75. The shaft 91 is provided with a bevel gear 92 meshing with a bevel gear 93 secured to the worm wheel 77 so that as the worm wheel 93 is rotated the shaft 96 is rotated thereby through the medium of the bevel gears 92 and 93. Consequently the link 87 is moved back and forth by the rotation of the crank 88 on the shaft 90, and the pawl 84 feeds the ratchet wheel 83 to actuate the shaft 62 for the purpose above described. A detent 94 (Fig. 4) prevents accidental backward rotation of the ratchet wheel 83. The automatic feed may be rendered ineffective, at will, by swinging the pawl 84, by means of a finger piece 95, out of engagement with the ratchet wheel 83 and against a stop 96 on the link 87.

The means to automatically render ineffective 100 the pressure increasing means, when the shuttles have been rolled to the proper thickness, may include a lever or feeler 100 pivoted by a stud 101 on a bracket 102 secured to the top plate 18. Said lever is provided with a nose 103 extending 105 through a slot 104 in the sleeve 49 and bearing against the cylindrical surface of the shaft 57, as indicated in dot and dash lines in Fig. 1, while the pressure increasing means is functioning; the nose being pressed against said shaft 110 by a spring 105.

A notch 106 in the shaft 51 is normally below the nose 103 and said shaft 53 moves upwardly until the notch reaches said nose when the latter is suddenly snapped into the notch 106 by 115 the spring 105, thus swinging an arm 108 of the lever 100 into the path of the finger piece 95 of the pawl 84. Upon a subsequent operation of the pawl 84 the latter, due to engagement of the finger piece 95 with the end 109 of the obstructing 120 arm 108, is swung about its pivot 85, out of engagement with the ratchet wheel 83, thus permitting the pawl carrying arm 86 to be operated 125 idly by the crank 88 of the shaft 90. Thus the upward feed of the shaft 57, and a consequent outward feed of the rollers 36 is automatically stopped; the oscillating movement of the roller means may continue however until the machine is stopped by the attendant by opening the switch 72.

The arm 108 is provided with a lip 109 which prevents it from moving in behind the finger piece 95 in case the notch moves to the nose 103 while the pawl 84 is in actuated position. Upon the return of the pawl 84, however, the 135 finger piece 95 moves clear of the lip 109 and the nose 103 then snaps into the notch 104, thus swinging the arm 108 into the path of the finger piece 95.

After the machine is stopped the lever 100 may 140 be actuated in a clockwise direction (Fig. 1) by a finger piece 110 to withdraw the nose 103 from the notch 106 of the shaft 57 to permit said shaft 57 to be lowered by means of the hand wheel 61, thus withdrawing the wedge 55 from 145 between the roller carriers 44. The roller supports 44 may then be moved towards each other to remove the roller from the shuttles to permit removal of the die, with the finished shuttles 150 from the chuck.

Having thus described the invention it will be understood that changes in the form, arrangements, proportions, sizes and details thereof may be resorted to without departing from the scope 5 of the invention.

I claim:—

1. In a machine for forming types on a type shuttle of a typewriting machine, the combination of a table, a chuck on said table, a die detachably supported in superposed relation in said chuck, said die having a circular aperture therein, types extending into said die from said aperture, said aperture being adapted to receive a curved shuttle blank, rollers to act on the shuttle blank, roller supporting means, means extending upwardly through said table and into said aperture, means associated with the roller supporting means to expand the latter, and means to oscillate said roller carrying means. 80
2. In a machine for forming types on a type shuttle of a typewriting machine, the combination of a machine frame, a chuck mounted on the machine frame, a die having a circular aperture detachably supported in said chuck, roller means, means to support the roller means centrally with reference to the chuck, said roller means extending through said chuck from its supported end to the jaws of the chuck, the roller means including a spindle, means connected to said spindle to reciprocate the roller means, and means including a shaft extending through said spindle whereby the roller means may be spread to increase the pressure thereof against said shuttle. 95
3. In a machine to form types on a segment, the combination of a curved die, having types depressed therein, over which a blank segment may be placed to expose one surface, a roller to engage the exposed surface of the segment to force the metal at the opposite surface into the type impressions of the die, a holder for said roller, and means to automatically reciprocate said holder to cause the roller to move back and forth over said segment to press the material thereof into the types of said die. 100
4. In a machine to form types on a segment, the combination of a curved die, having types depressed therein, over which a blank segment may be placed to expose one surface, a roller to engage the exposed surface of the segment to force the metal at the opposite surface into the type impressions of the die, a holder for said roller, a shaft connected to said holder, an arm on said shaft, a link connected to said arm, a disk connected to said link, and means to rotate said disk to reciprocate said shaft and said holder to cause said roller to move back and forth over the segment to press the material thereof into the types of said die. 115
5. In a machine to form types on a segment, the combination of a curved die, having types depressed therein, over which a blank segment may be placed to expose one surface, a roller to engage the exposed surface of the segment to force the metal at the opposite surface into the type impressions of the die, a holder for said roller, a shaft connected to said holder, an arm on said shaft, a link connected to said arm, a disk connected to said link, power means, and gearing connecting said power means with said disk to drive the latter continually to reciprocate said link to thus reciprocate said shaft and said holder to cause the roller to move back and forth over said segment to press the material thereof into the types of said die. 120
6. In a machine to form a type shuttle, the combination of a die, means to hold said die, said die having a curved aperture into which may be inserted a partially formed curved shuttle, roller means engaging the shuttle to press it against the die, means to effect a reciprocatory rotative movement between the die and the roller means to flow the metal of the shuttle into the types of the die to form types on the face of the shuttle, and means to automatically increase the pressure of the roller means against said shuttle as the reciprocation of the roller means continues. 125
7. In a machine to form types on a segment, the combination of a curved die, having types depressed therein, over which a blank segment may be placed to expose one surface, a roller to engage the exposed surface of the segment to force the metal at the opposite surface into the type impressions of the die, a holder for said roller, means to automatically reciprocate said holder to cause the roller to move back and forth over said segment to press the material thereof into the types of said die, and means to automatically actuate said support during the reciprocation thereof to increase the pressure of said roller against said segment. 130
8. In a machine to form types on a segment, the combination of a curved die, having types depressed therein, over which a blank segment may be placed to expose one surface, a roller to engage the exposed surface of the segment to force the metal at the opposite surface into the type impressions of the die, a holder for said roller, means to automatically reciprocate said holder to cause the roller to move back and forth over said segment to press the material thereof into the types of said die, means to actuate said holder during the reciprocation thereof to increase the pressure of said roller against said segment, and means operable by the holder reciprocating means to operate the holder actuating means periodically. 135
9. In a machine to form types on a segment, the combination of a curved die, having types depressed therein, over which a blank segment may be placed to expose one surface, a roller to engage the exposed surface of the segment to force the metal at the opposite surface into the type impressions of the die, a holder for said roller, means to automatically reciprocate said holder to cause the roller to move back and forth over said segment to press the material thereof into the types of said die, and means to automatically actuate said holder during the reciprocation thereof to increase the pressure of said roller against said segment, the last mentioned means including a ratchet wheel, means connecting the ratchet wheel with said holder, a pawl to engage said ratchet, and a shaft operable by said holder reciprocating means to actuate said pawl to actuate said ratchet. 140
10. In a machine to form types on a segment, the combination of a curved die, having types depressed therein, over which a blank segment may be placed to expose one surface, a roller to engage the exposed surface of the segment to force the metal at the opposite surface into the type impressions of the die, a holder for said roller, means to automatically reciprocate said holder to cause the roller to move back and forth over said segment to press the material thereof into the types of said die, means to automatically actuate said holder during the reciprocation thereof to increase the pressure of said roller against said segment, the last mentioned means being operable by the holder reciprocating means, 145

and means to render ineffective the pressure increasing means.

11. In a machine to form types on a segment, the combination of a curved die, having types depressed therein, over which a blank segment may be placed to expose one surface, a roller to engage the exposed surface of the segment to force the metal at the opposite surface into the type impressions of the die, a holder for said roller, means to automatically reciprocate said holder to cause the roller to move back and forth over said segment to press the material thereof into the types of said die, means to automatically actuate said support during the reciprocation thereof to increase the pressure of said roller against said segment the last mentioned means being operable by the holder reciprocating means periodically, and means controlled by the pressure increasing means to render the latter ineffective when the segment has been rolled down to the proper thickness.

12. In a machine for forming types on a type shuttle of a typewriting machine, the combination of a die, means to hold said die, said die having a circular aperture, types extending into said die from said aperture, said aperture adapted to receive a shuttle blank, roller means to operate in said aperture against said shuttle, means to reciprocate said roller means, means extending through said reciprocating means to increase the pressure of the roller means against the shuttle, and means to automatically actuate the pressure increasing means.

13. In a machine for forming types on a type shuttle of a typewriting machine, the combination of a die, means to hold said die, said die having a circular aperture, types extending into said die from said aperture, said aperture adapted to receive a shuttle blank, roller means to operate in said aperture against said shuttle, means to reciprocate said roller means, means extending through said reciprocating means to increase the pressure of the roller means against the shuttle, means to automatically actuate the pressure increasing means, and means controlled by the pressure increasing means to render the automatic means ineffective.

14. In a machine for forming types on a type shuttle of a typewriting machine, the combination of a die, means to hold said die, said die having a circular aperture, types extending into said die from said aperture, said aperture adapted to receive a shuttle blank, a roller to operate on the blank, a carrier for said roller, a support for said carrier, a hollow shaft extending from said support, means connected to the hollow shaft to reciprocate the carrier with the roller and its support, a shaft extending through said hollow shaft, means to actuate the inner shaft axially, means operable by the inner shaft to move the roller carrier outwardly on said support to increase the pressure of said roller on said shuttle blank, the inner shaft having a shoulder, and means engaging with said shoulder to render ineffective the inner shaft actuating means.

15. In a machine for forming types on a type shuttle of a typewriting machine, the combination of a die, means to hold said die, said die having a circular aperture, types extending into said die from said aperture, said aperture adapted to receive a shuttle blank, a roller to operate on the blank, a carrier for said roller, a support for said carrier, a hollow shaft extending from said support, means connected to the hollow shaft to reciprocate the carrier with the roller and its sup-

port, a shaft extending through said hollow shaft, means to actuate the inner shaft axially, and means operable by the inner shaft to move the roller carrier outwardly on said support to increase the pressure of said roller on said shuttle blank.

16. In a machine for forming types on a type shuttle of a typewriting machine, the combination of a die, means to hold said die, said die having a circular aperture, types extending into said die from said aperture, said aperture adapted to receive a shuttle blank, a roller to operate on the blank, a carrier for said roller, a support for said carrier, a hollow shaft extending from said support, an arm on said hollow shaft, a rotating shaft, a crank on the rotating shaft, a link connecting said arm and said crank to reciprocate the hollow shaft while the other shaft rotates to reciprocate the roller back and forth over the shuttle blank, a shaft extending through said hollow shaft, and means operable by the inner shaft to move the roller carrier outwardly on its support to increase the pressure of the roller on the shuttle blank.

17. In a machine for forming types on a type shuttle of a typewriting machine, the combination of a die, means to hold said die, said die having a circular aperture, types extending into said die from said aperture, said aperture adapted to receive a shuttle blank, a roller to operate on the blank, a carrier for said roller, a support for said carrier, a hollow shaft extending from said support, means connected to the hollow shaft to reciprocate the carrier with the roller and its support, a shaft extending through said hollow shaft, a nut threaded on the inner shaft, means to rotate said nut to adjust the inner shaft axially and means operable by the axial adjustment of the inner shaft to move the roller carrier outwardly on its support to increase the pressure of the roller against the shuttle blank.

18. In a machine for forming types on a type shuttle of a typewriting machine, the combination of a die, means to hold said die, said die having a circular aperture, types extending into said die from said aperture, said aperture adapted to receive a shuttle blank, a roller to operate on the blank, a carrier for said roller, a support for said carrier, a hollow shaft extending from said support, means connected to the hollow shaft to reciprocate the carrier with the roller and its support, a shaft extending through said hollow shaft, a nut threaded on the inner shaft, gearing to rotate said nut to adjust the inner shaft axially, means including a finger piece to actuate said gearing, and means operable by the axial movement of the inner shaft to move the roller carrier outwardly on its support to increase the pressure of the roller on the shuttle blank.

19. In a machine to form types on a segment, the combination of a curved die, having types depressed therein, over which a blank segment may be placed to expose one surface, a roller to engage the exposed surface of the segment to force the metal at the opposite surface into the type impressions of the die, a holder for said roller, means to reciprocate said holder to cause said roller to move back and forth over said segment, means including a shaft to increase the pressure of said roller on said segment, means including a pawl and a ratchet to actuate said shaft axially, means operable by the reciprocating means to actuate said pawl, and means controlled by said shaft to render said pawl inactive to thus render ineffective the pressure increasing means.

20. In a machine to form types on a segment, the combination of a curved die, having types depressed therein, over which a blank segment may be placed to expose one surface, a roller to engage the exposed surface of the segment to force the metal at the opposite surface into the type impressions of the die, a holder for said roller, means to reciprocate said holder to cause said roller to move back and forth over said segment, means including a shaft to increase the pressure of said roller on said segment, means including a pawl and ratchet to actuate said shaft axially, means operable by the reciprocating means to actuate said pawl, a bell crank, a nose thereon bearing against said shaft, said shaft having a notch therein into which the nose may enter when the segment has been rolled to the proper thickness, and a projection on said pawl into the path of which the bell crank moves when the nose moves into the notch so as to render said pawl ineffective. 80
21. In a machine for making type shuttles for a typewriting machine, the combination of a die having a circular aperture, types extending into said die from said aperture, said aperture being adapted to receive two oppositely disposed shuttle blanks, means to hold said die, a circular support in said aperture, said support having a transverse slot therein, two carriers in said slot, two rollers, one on each carrier, a hollow shaft extending from said support, means to reciprocate said shaft to thus reciprocate the roller over said shuttle blanks, a wedge between said carriers, and means including a shaft extending through said hollow shaft whereby the wedge may be operated to spread the roller carriers to increase the pressure of the rollers on said shuttle. 85
22. In a machine for making type shuttles for a typewriting machine, the combination of a die having a circular aperture, types extending into said die from said aperture, said aperture being adapted to receive two oppositely disposed shuttle blanks, means to hold said die, a circular support in said aperture, said support having a transverse slot therein, two carriers in said slot, two rollers, one on each carrier, a hollow shaft extending from said support, means to reciprocate said shaft to thus reciprocate the roller over said shuttle blanks, a wedge between said carriers, a shaft extending through said hollow shaft, means to actuate the inner shaft axially to actuate the wedge to spread said roller carriers to increase the pressure of the rollers on said shuttle blanks, means to prevent rotation of the inner shaft, and means to pivotally connect the wedge with the inner shaft so that the wedge may reciprocate with the roller carriers. 90
23. In a machine for forming types on a type shuttle of a typewriting machine, the combination of a die, means to support said die, said die having an aperture and types extending from the aperture, the aperture to receive a segmental type shuttle blank, means including a roller to act on the inner surface of the shuttle blank, and means to effect a relative rotative movement between the die and the roller means, the roller means extending into the die aperture from the side at which the supporting means is located so as to permit removal of the shuttle at the opposite side of the die without removing the roller means. 95
24. In a machine for forming types on a type carrier of a typewriting machine, the combination of a die, means including a frame at one side of the die to support the latter, said die having an aperture and types extending from the aperture, the aperture to receive a segmental type shuttle blank, means including a roller to act on the inner surface of the carrier blank, and means to effect a relative rotative movement between the die and the roller means, the roller means being supported independently of said die on said frame and extending into the die aperture from the side at which the frame is located so that the carrier may be removed from the die without removing the roller means. 100
25. In a machine for making a type carrier for a typewriting machine, the combination of two devices, namely a die having types thereon, and co-operative means, a support for the die, the co-operative means being also mounted on said support and extending to the die from the side at which the supporting means is located so as to permit the removal of the type carrier at the opposite side of the die without removing the cooperative means; and means to rotate one of said devices with respect to the other to act on said type carrier to form the types thereon. 105
26. In a machine for forming types on segmental type shuttles, the combination of a matrix comprising a plurality of sections forming a circular opening into which two shuttle blanks may be placed in oppositely disposed relation, two rollers one to act on each shuttle blank to displace material therefrom into types of the matrix, two oppositely disposed carriers one for each roller, a support to guide said carriers, means to effect a relative rotative movement between said support and the matrix to cause the rollers to roll over the shuttle blanks, and a device to engage both roller carriers to move the rollers outwardly to increase the pressure thereof against the shuttles. 110
27. The combination of a die having a circular aperture formed by a plurality of segmental sections disposed end to end, rollers to act on the work placed within die aperture, roller carriers one for each roller, a support upon which the roller carriers are mounted for outward movement, and means including a device common to all of the roller carriers to move them outwardly on said support. 115
28. The combination of a die having a circular aperture formed by a plurality of segmental sections disposed end to end, rollers to act on the work placed within die aperture, roller carriers one for each roller, a support upon which the roller carriers are mounted for outward movement, means including a device common to all of the roller carriers to move them outwardly on said support, and means independent of said device to actuate said roller carriers. 120
29. The combination of a die having a circular aperture formed by a plurality of segmental sections disposed end to end, rollers to act on the work placed within the die aperture, roller carriers one for each roller, a support upon which the roller carriers are mounted for outward movement, means including a device common to all of the roller carriers to move them outwardly on said support, means to hold said die, a shaft connected to the roller support, and means connected to said shaft to oscillate it and the rollers. 125
30. The combination of a die having a circular aperture formed by a plurality of segmental sections disposed end to end, rollers to act on the work placed within the die aperture, roller carriers one for each roller, a support upon which the roller carriers are mounted for outward movement, a device common to all of the roller carriers 130
- 75

to move them outwardly on said support, means to hold said die, a hollow shaft connected to said roller support, means to oscillate the shaft to cause the rollers to act on the work, a rod extending through the hollow shaft, and means to actuate said rod to operate said device and thereby move the roller carriers outwardly to increase the pressure of the rollers against the work.

31. The combination of a die having a circular aperture formed by a plurality of segmental sections disposed end to end, rollers to act on the work placed within the die aperture, roller carriers one for each roller, a support for said roller carriers, said support having a slot with offsets in the walls thereof, each roller carrier being shaped to fit into the slot to be guided thereby, and means including a device to move the roller carriers outwardly in said slot to increase the pressure of the rollers on said work.

32. The combination of a die having a circular aperture formed by a plurality of segmental sections disposed end to end, rollers to act on the work placed within the die aperture, roller carriers one for each roller, a support for said roller carriers, said support being slotted to guide the roller carriers, the roller carriers having slots in their inner ends, and a wedge extending into said slots to move the roller carriers outwardly on the support to increase the pressure of the rollers on said work.

33. The combination of a matrix having a circular aperture therein into which an article may be placed to be operated upon, a fixed holder for said matrix, two rollers to act on said article to displace the material to conform with the shape of the face of matrix, two roller carriers one for each roller, a support for the roller carriers, means to oscillate said support to effect a reciprocatory movement of the rollers over the article, a wedge between said roller carriers, a rod by which the wedge may be operated, means to prevent rotation of said rod, means to actuate said rod axially to spread the roller carriers by said wedge, and means to pivotally connect the wedge with the rod so that the wedge may oscillate with the roller carriers and so that the wedge may be retracted thereby to enable the roller carriers to be moved inwardly.

34. The combination of a die having a circular aperture therein, a holder therefor, roller means in said aperture to operate on an article in said die, means to expand the roller means to increase its pressure against the article, the expanding means including a rod, means to actuate said rod, a toothed wheel, and a detent co-operating with the toothed wheel to hold the expanding means.

35. The combination of a die having a circular aperture therein, a holder therefor, roller means in said aperture to operate on an article in said die, means to expand the roller means to increase its pressure against the article, the expanding means including a rod, means to prevent rotation of said rod, a gear threaded onto said rod to move the latter axially to expand the roller means, means to actuate said gear, a toothed wheel associated with the last mentioned means, and a detent co-operating with the toothed wheel to hold the expanding means.

36. The combination of a die having a circular aperture therein, a holder therefor, roller means in said aperture to operate on an article in said die, means to expand the roller means to increase its pressure against the article, the expanding means including a rod, means to prevent rotation of the rod, a nut threaded on

said rod, means to rotate the nut to cause the rod to move axially to expand the roller means, and means to hold the nut against movement in the same direction as the rod.

37. In a machine for forming types on a type shuttle of a typewriting machine, the combination of a table, a chuck on said table, a die detachably supported in said chuck, said die having a vertically disposed circular aperture therein, types extending into said die from said aperture, said aperture being adapted to receive a curved shuttle blank, roller means extending upwardly through said table and into said aperture, means supported by the roller means to expand the latter, and means to cause an oscillatory movement between the chuck and the roller means.

38. In a machine to form types on a segment, the combination of a curved die having types depressed therein over which a blank segment may be placed to expose one surface, a holder for said die, a roller to engage the exposed surface of the segment to force the metal at the opposite surface into the type impressions of the die, a holder for said roller, and means to automatically reciprocate one of said holders to cause a relative movement of the roller back and forth over said segment to press the material thereof into the types of said die.

39. The combination of a die having type intaglios, means to hold said die, said die having a curved aperture into which may be inserted an article to be operated upon, roller means engaging said article to press it against the die, means to effect a relative movement between the die and the roller means to flow some of the metal of the article into the intaglios of the die to form cameos on the face of the article, actuating means to expand the roller means, manual means to operate the actuating means to set the roller means against the article, and automatic means to operate the actuating means to increase the pressure of the roller means against said article.

40. In a machine for forming types on a type shuttle of a typewriting machine, the combination of a die, a holder for said die, said die having a circular aperture, types extending into said die from said aperture, said aperture adapted to receive a shuttle blank, roller means to operate in said aperture against said shuttle, a holder for said roller, means to reciprocate one of said holders, and means extending through said reciprocating means to increase the pressure of the roller means against the shuttle.

41. In a machine to form types on a segment, the combination of a curved die, having types depressed therein over which a blank segment may be placed to expose one surface, a roller to engage the exposed surface of the segment to force the metal at the opposite surface into the type impressions of the die, a holder for said roller, actuating means to effect a relative movement between the roller and the segment, means including a shaft to increase the pressure of said roller on said segment, means including a pawl and a ratchet to actuate said shaft axially, means operable by the actuating means to actuate said pawl, and means controlled by said shaft to render said pawl inactive to thus render ineffective the pressure increasing means.

42. The combination of a die, means to hold said die, said die having a circular aperture to receive an article, roller means to operate in said aperture against said article, actuating

means to effect a relative motion between the roller means and the article, means to increase the pressure of the roller means against the article, means to automatically actuate the pressure increasing means, and means to automatically render the pressure increasing means ineffective.

43. The combination of a die, means to hold said die, said die having a circular aperture adapted to receive an article, roller means to operate in said aperture against said article, means to effect a relative motion between the roller means and the article, means including a shaft to increase the pressure of the roller means against the article, means to automatically actuate the pressure increasing means, means to render the automatic means ineffective, and means on said shaft to effect the actuation of the rendering means.

44. The combination of a die, means to hold said die, said die having a circular aperture adapted to receive an article, roller means to operate in said aperture against said article, means to effect a relative motion between the roller means and the article, means including a shaft to increase the pressure of the roller means against the article, means to automatically actuate the pressure increasing means, said shaft having a notch therein, and means to render the automatic means ineffective, the rendering means including a feeler to engage the surface of said shaft and entering said notch to render ineffective the automatic means when the article has been reduced to the proper thickness.
